UNITED STATES PATENT OFFICE.

ISRAEL GRAFUIS, OF ALEXANDRIA, PENNSYLVANIA.

FIRE-ESCAPE.

Specification of Letters Patent No. 30,219, dated October 2, 1860.

To all whom it may concern:

Be it known that I, ISRAEL GRAFUIS, of Alexandria, in the county of Huntingdon and State of Pennsylvania, have invented 5 a new and useful Improvement in Portable Fire-Escapes; and I do hereby declare that the following is a full, clear, and exact description of the same, reference being had to the accompanying drawing, forming a 10 part of this specification, in which—

Figure 1, represents a longitudinal vertical section of my invention, the line x, x , Fig. 2 indicating the plane of section. Fig. 2, is a plan or top view of the same.

15 Similar letters of reference in both views indicate corresponding parts.

The object of my invention is to supersede the use of a strong canvas sheet with loops, which is sometimes held under the window 20 at which any person is situated by eight or ten persons and the party above leaps out of the window in the middle of the sheet, which catches him uninjured. This mode of escape although numberless experiments 25 have proved it to be a safe and effectual one, is objectionable, because in the confusion and excitement of a fire it is not always easy to find eight or ten men of sufficient strength to hold on to the canvas. This 30 difficulty I have avoided and I provide the means to catch persons leaping out of a window without requiring the assistance of more than one or two persons, by my invention which consists in the employment of 35 a strong sheet of canvas, or india-rubber, cloth, or other suitable material stretched across a folding frame and covered by cushions, in such a manner, that the same when placed under a window affords a safe 40 landing place for persons leaping out.

My invention consists also in securing to the edge of the frame and all around the same a strong, india-rubber tube to prevent 45 injury in case a person alights on the frame close to its edges.

To enable those skilled in the art to make and use my invention I will proceed to describe its construction and operation with reference to the drawing.

50 A, represents a frame of four strong timbers a, b , secured together in the corners by means of dowels or in any other suitable manner, two of the timbers b , are cut through in the middle and the two halves

are united by hinges c , so as to allow the 55 frame to fold up, and the other timbers a , are provided with handles d , which serve to carry the frame from place to place and to adjust it on the desired spot, and legs, e , support the whole at a certain height from the 60 ground. Additional legs may be placed in the center of the timbers b , so as to support more firmly the center of the frame and to take off the strain from the hinges c , in case a person leaps down from a window 65 right in the center of the frame; but in case such legs are used they have to be made so that they fold up, and that they do not interfere with the folding up of the frame A.

Each half of the frame A is covered over 70 by a stout sheet B, of india rubber or other elastic material, which is firmly secured all around on the upper sides of the timbers a , and b , and a cushion C stuffed with hair or any other suitable substance is placed on 75 the upper surface of the sheet B. The softness of the cushion C, together with the elasticity of the sheet serves to break the fall of a person leaping down from a window and to prevent injury. The middle portion 80 of the sheet B, may be strengthened by extra bands e' of some elastic material, and a stout tube D, of india rubber or of some other soft and elastic material is secured all around the edges of the frame A, by means 85 of leather straps f or by any other suitable means. The object of this tube is to prevent persons rolling down over the edges of the frame.

This apparatus can be made very cheap 90 it is light and easily handled by four men and it can be carried to the place where it may be needed either on a separate truck or on the engine or hose cart or on the ordinary hook and ladder truck. 95

What I claim as new and desire to secure by, Letters Patent, as a new article of manufacture is—

A portable fire escape constructed of a folding frame A, covered by an elastic sheet 100 B, and cushion C, and having its edges protected by a stout elastic tube D, and operating in the manner and for the purpose herein set forth.

ISRAEL GRAFUIS.
